UNITED STATES PATENT OFFICE.

JAMES J. CORBETT CULVER, OF CAMDEN ON GAULEY, WEST VIRGINIA.

KNIFE.

Application filed May 27, 1925, Serial No. 33,226. Renewed March 29, 1927.

This invention relates to improvements in knives, and has for its primary object the provision of a sharpening means for the blade or blades thereof, such sharpening means being in the nature of a whetstone or the like which forms a portion of the handle of the knife and is readily removable for the application of the blade when it is desired to sharpen the latter.

This invention also consists in certain other features of construction and in the combination and arrangement of the several parts, to be hereinafter fully described, illustrated in the accompanying drawings, and specifically pointed out in the appended claims.

In describing my invention in detail, reference will be had to the accompanying drawings wherein like characters denote like or corresponding parts throughout the several views, and in which:

Figure 1 is a side elevation of a pocket knife constructed in accordance with the present invention,

Fig. 2 is a similar view with parts removed,

Fig. 3 is a sectional view taken on line 3—3 of Fig. 1, and

Fig. 4 is a detail view of the sharpening stone and its housing.

Referring to the drawings in detail the pocket knife as shown is of the usual construction and the reference numerals 1 and 2 indicate the plates between which is mounted the blade 3. The handle butts 4 and 5 are fixed to the plates through the medium of a pin 6' which also passes through a spacing block 7 for the plates 1 and 2 as clearly shown in Fig. 3. Extending inwardly from the handle butt 4 is a stud 6 adapted to be received in a recess 7' formed in one end of the housing 8 and the sharpening stone 9. The housing 8 for the stone 9 is formed with an outer wall 10, side walls 11 and 12 and end walls 13 and 14. Extending inwardly from the side walls 11 and 12 and the end wall 13 are tongues 15 engaging the sharpening stone for retaining the same operatively associated within the housing. The end wall 14 is provided with a projection 16 which cooperates with the tongues 15, and a recess 17 extends through the end wall 14 for receiving the inner end of a sliding block 17' having a projection 16' thereon for that purpose. The sliding block is formed with a slot 18 through

which passes a pin 19 which also passes through the handle butt 20 and a cover plate 21 which is arranged above the spring chamber 22, for retaining these parts in position as shown in Fig. 3. The sliding block is substantially T-shaped in configuration and has passing therethrough a pin 23 which is arranged in the spring chamber and is acted upon by a leaf spring 24; and in order that the sliding block can be conveniently operated there is provided in its outer end a finger-nail engaging groove 25.

A handle plate 26 is secured to the plate 2 and arranged between the handle butts 5 and 20.

From the above description and drawings it will be readily apparent that the device which forms the subject-matter of the present invention is extremely simple and forms a portion of the knife handle, such portion being readily removable, whereby it may be used for sharpening the blade 3 of the knife shown.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A knife handle of the character described comprising a pair of spaced plates, butts and a handle plate fixed to one of said spaced plates, a housing including outer side and end walls removably associated with the other of said spaced plates, a sharpening stone received in said housing, and tongues formed on the side and end walls of said housing for retaining said stone in the housing.

2. A knife handle of the character described comprising a pair of spaced plates, a handle butt fixed to one of said spaced plates, a stud extending inwardly from the handle butt, a sliding block mounted for movement adjacent the opposite end of said spaced plate, a sharpening device removably associated with said plate through the medium of the stud and sliding block, and means including butts secured to the opposite ends of said spaced plates to complete the handle structure.

3. A knife handle of the character de-

scribed comprising a pair of spaced plates, means associated with one of said spaced plates to form one portion of said handle, a butt secured to one end of the other of said spaced plates, a stud projecting from said butt, a substantially T-shaped sliding block mounted for movement adjacent the opposite end of the last-mentioned spaced

plate, a sharpening element provided with end recesses for receiving the stud and the 10 adjacent end of the sliding block respectively, and a cover plate overlying the sliding block.

In testimony whereof I affix my signature.

JAMES J. CORBETT CULVER.
